UNITED STATES PATENT OFFICE.

CYRUS LEWIS, SR., OF LORAIN, OHIO.

RIFFLING-MACHINE.

1,017,569.

Specification of Letters Patent. Patented Feb. 13, 1912.

Application filed October 19, 1910. Serial No. 587,974.

To all whom it may concern:

Be it known that I, CYRUS LEWIS, Sr., a citizen of the United States, residing at Lorain, in the county of Lorain and State 5 of Ohio, have invented new and useful Improvements in Riffling-Machines, of which the following is a specification.

This invention relates to a machine for riffling pipes.

10 Heretofore, it has been common to riffle the interior of pipes by passing them through rolls, one of which was provided with spiral ribs, and the other of which was provided with spiral indentations to receive 15 or to coat with the ribs. After the pipe was thus rifled or corrugated it was welded together and sized. This latter operation resulted in the depression of the ripples in the pipe and frequently reduced their depth to 20 such an extent that the ripples were useless.

It is the object of this invention to obviate the difficulties experienced and the faulty results produced in such mechanism and broadly speaking consists in providing the 25 sizing rolls and bell with means for internally riffling the pipe as it is sized.

Further objects of the invention will appear as the following specific description is read in connection with the accompanying 30 drawings which form a part of this application, and in which:

Figure 1 is a side elevation of the machine. Fig. 2 is an end elevation. Fig. 3 is a side elevation of the sizing bell or core. Fig. 4 is a detail perspective view of one of the 35 riffling rolls and its supporting frame removed from the bell or core. Fig. 5 is a detail perspective view of a shim used in connection with the roller frame for elevating 40 the roller.

Referring more particularly to the drawing 1 represents a suitable support from which depend the separate arms 2 having journaled therein the sizing rollers 3 and 45 4, both of which are provided with semi-cylindrical peripheral grooves 5 to receive the pipe. The core or forming bell is shown at 6 which comprises an elongated circular member having a pointed head 7 50 adapted to project slightly into the circular pass formed by the grooves 5 and having its rear end provided with a triangular or

square socket 8 which is adapted to receive the square or triangular end 9 of the driving shaft 10. This shaft is provided with a suitable gear 11 on its rear end which is adapted to mesh with a driving gear (not shown). The shaft 10 is preferably slidably mounted within its bearings so as to permit the removal of the pipe after being properly rifled. The core or bell 6 is provided with a plurality of diagonally extending recesses 12 in which are removably fitted bearing frames 13 having suitable anti-friction bearings 14 mounted therein to receive the short 65 pintles 15 of the riffling rollers 16. These rollers are held in position by suitable side bars 17 which are bolted to the frame 13. Two of these riffling rollers are mounted upon one side of the core adjacent the ends 70 thereof and extend in the same direction in parallel lines and one of the rollers is arranged on the opposite side intermediate the end. These rollers and their frames may be raised by the shims shown in Fig. 5 when 75 said shims are placed beneath the frames in the sockets 12 so that the riffling in the inner side of the pipe will have its depth increased or decreased as desired. It will of course be understood that the sockets and 80 roller frames together with their rollers may be set at any angle desired in the core so as to secure the desired pitch in the riffling. When the pitch of the rollers is changed it is necessary to also change the speed of rotation of the shaft to correspond. 85

The term riffling, used throughout the specification and in the claims, is a common expression used in tube mills to define diagonal corrugating, grooving or ribbing and 90 the word should therefore be accepted with this definition.

Having thus described the invention, what is claimed is—

1. In a riffling machine, the combination 95 with a sizing device, of a sizing core, and rollers carried by the sizing core for riffling the interior of the pipe.
2. In a pipe riffling machine, the combination with a pair of sizing rolls, of an interior 100 sizing core, and a plurality of riffling rollers carried by the core.
3. In a pipe riffling machine, the combination with a pair of sizing rolls, of an in-

terior sizing core, a plurality of riffling rollers arranged diagonally across the axis of the core, and means to adjust the height of the rollers with relation to the surface of the core.

4. In a pipe riffling machine, the combination with a pair of sizing rolls, of an interior sizing core having sockets therein, and

a plurality of riffling rollers removably mounted in said sockets.

In testimony whereof I affix my signature in presence of two witnesses.

CYRUS LEWIS, Sr.
